A. A. GORDON

COLOR INDICATOR FOR WEFT REPLENISHING LOOMS

Filed Oct. 19, 1926

UNITED STATES PATENT OFFICE.

ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

COLOR INDICATOR FOR WEFT-REPLENISHING LOOMS.

Application filed October 19, 1926. Serial No. 142,773.

This invention relates to improvements in color indicators for weft replenishing looms and it is the principal object of the invention to provide means for procuring the color indication on certain pattern controlling mechanisms, such, for instance, as the Knowles head, at an earlier time in the cycle of the pick than has been possible heretofore.

10 In multi-color weft replenishing mechanisms the bobbins are usually arranged in groups according to distinctive characteristics such, for instance, as color, and there is a selecting mechanism which chooses the correct color to be inserted into the exhausted shuttle. By means of releasing devices commonly termed cradles the selected bobbin is passed from the proper stack to a transfer position common to all the stacks and it is necessary that the bobbin start toward transfer position sufficiently early in the pick to arrive under the transerrer arm before the latter starts to move down. When weft replenishing mechanisms of the multi-color type have been employed heretofore in connection with the Knowles head it has been found that the speed of the loom is sufficiently slow so that the bobbin has sufficient time to arrive at transfer position when the color selector is operated directly from the means which moves the boxes and in strict time with the latter due to the fact that worsted looms which employ the Knowles head run at a comparatively slow rate of speed.

25 Recent developments in automatic silk looms have brought into use a form of Knowles head somewhat lighter than that used on the worsted loom and these silk looms run at a much faster speed than the ordinary worsted loom. As a result, it is found that when silk looms have the form of connection between the boxes and the color selector usual in worsted looms insufficient time is allowed for the dropping of the selected bobbin to transfer position. It is an important object of my present invention to provide improved means for completing the movement of the color selector prior to arrival of the boxes at their ultimate positions, to the end that the color selector may start its bobbin releasing movement earlier in the pick than has been pos-

sible heretofore when the Knowles head has been employed.

A further and more particular object 55 of my invention is to employ parts customarily found on the Knowles head for actuating the color selector, said parts including a variation of the ordinary drop weight, the office of which is to move the 60 vibrator connector below the center of the vibrator gear in order to be locked in either raised or lowered position.

The Knowles head employs among other things a vibrator lever operable by the pattern chain and having mounted thereon a vibrator gear to which is attached a vibrator connector, the connector actuating either a harness or the levers which control the boxes, and it is a more particular object of my invention to derive the motion for controlling the color slide from the upward movement of the vibrator connector.

With these and other objects in view which will appear as the description proceeds, my 75 invention resides in the combination and arrangement of parts hereinafter described and set forth in the claims.

In the accompanying drawings wherein I have shown a convenient embodiment of my 80 invention,

Fig. 1 is a rear elevation of the Knowles head and certain parts controlled thereby showing my invention applied thereto,

Fig. 2 is a fragmentary view similar to a 85 portion of Fig. 1 but with the parts in a different position,

Figs. 3 and 4 are vertical sections on lines 3—3 and 4—4, respectively, of Fig. 1,

Fig. 5 is an enlarged vertical section on 90 line 5—5 of Fig. 1,

Fig. 6 is a section on line 6—6 of Fig. 1, and

Fig. 7 is a diagrammatic view showing the relation between the usual color selector of 95 the ordinary multi-color weft replenishing mechanism and my improved controlling device therefor.

Referring to the drawings I have indicated a loom arch 10 and a head frame 11 100 bolted thereto and having oppositely rotating mutilated upper and lower cylinder gears 12 and 13, respectively, driven by mechanism not shown but well understood.

A pattern cylinder 14 is provided with a pattern chain 15 provided as shown in Fig. 5 with balls 16 and sinkers 17 which are located under vibrator levers 18 which move 5 pivotally about a heel pin 19 supported in the head frame. Upward movement of the right hand ends of the vibrators is prevented by a guard 20 and there is pivotally mounted on the opposite end of each vibrator lever a vibrator gear 21. Connected pivotally as at 22 to each of the vibrator gears 21 is a vibrator connector 23, two vibrator levers and connectors being shown herein to correspond to a loom having four 10 boxes on the end opposite the replenishing mechanism.

The mechanism for controlling the boxes includes two levers 24 and 25, respectively, the former being pivoted at 26 and having 20 direct connection as at 27 with a box lifting chain 28 and being attached at the upper end thereof to one of the vibrator connectors. The other lever 25 has mounted for free rotation on the lower end thereof a sheave 29 25 around which extends the chain 28 and the upper end of said lever 25 is operatively connected to the other of the vibrator connectors 23. A guide sheave 30 pivoted on a fixed stud 31 guides the chain 28 toward the 30 boxes.

In the operation of the device thus far described the cylinders 12 and 13 rotate constantly in opposite directions and the pattern chain 15, shown herein as being two 35 spaces wide, raises and lowers the vibrator levers 18 in predetermined sequence depending upon the order in which the shuttles are to become active so that the vibrator gears are presented to one or the other of said 40 mutilated cylinders. As the gears 21 rotate the levers 24 and 25 will be oscillated either to the right or to the left so as to give the box lifter chain 28 four different positions. This part of the mechanism is well understood 45 and is known as the Knowles head and may be the same as that set forth in Patent No. 1,384,992.

In carrying my invention into effect I 50 make use of a slight variation of the usual form of drop weight, the purpose of which as previously stated is to move the point of attachment between the connectors 23 and the vibrator gears 21 to points below the center of the gears in either position of the latter, and in carrying my invention into effect I provide a pair of drop weight levers 55 40 each pivoted on the usual stud 41 but provided with an arm 42 attached to a spring 43, the upper end of which is held to a fixed 60 part of the loom as at 44. The arms 42 and springs 43 constitute a slight variation in the usual construction of the drop weight, the springs serving to hold the drop weight levers against the connectors 23.

In carrying my invention into further ef-

fect I provide each drop weight lever 40 with a pawl 45 yieldingly held by spring 46 in the position shown in Fig. 1. Each pawl cooperates with a ratchet 47, there being two ratchets shown herein, and each ratchet has integral therewith a cam disc 48 composed of high and low points 49 and 50, respectively. Said discs and ratchets are freely rotatable on a stud 51 held in a small stand 52 fixed with respect to the head frame. As 75 the vibrator connectors 23 rise due to the rotary movement of the vibrator gears the pawls 45 will give an angular movement to the ratchets and discs.

Referring to Fig. 7 it will be seen that the 80 weft magazine M is provided with a plurality of vertically movable slides 53 and is further provided with a color slide 54 movable horizontally in bearings 55 forming part of the magazine under influence of a bell crank lever 56 moving about a fixed pivot 57. A spring 58 is interposed between a fixed part of the magazine and the bell crank lever and by means of a grooved collar 59 which has contact with the upper end of the bell crank lever the color slide 54 is moved back and forth so that fingers, one of which is indicated at 60, may cooperate with the lugs 61 forming parts of the slides 53. It is to be understood that the longitudinal 85 position of the color slide 54 must agree with the active shuttle and that said color slide is given an angular movement both at the time of indication of weft exhaustion and also at the time of releasing the fresh 90 bobbin to be inserted in the exhausted shuttle. The color slide and parts associated therewith as shown in Fig. 7 may be substantially the same as shown in Patent No. 1,030,748.

In order to control the position of the color slide 54 by means of the previously 100 described discs 48 I employ a system of compound levers similar to those usually employed on box motions more particularly of the so-called Crompton type, and in carrying this feature of my invention into effect I provide a relatively short lever 70 pivoted on the stud 41 and having an upwardly extending arm with a rounded surface 71 adapted to enter the low points 50 of the discs or the slight recesses 72 formed in the face of the high points 49, said recesses serving to position the discs and ratchets. A relatively longer control lever 73 is pivoted as at 74 to the lower end of the shorter lever 70 and is also provided at the upper end thereof with a rounded end 75 similar to the rounded end 71. The lower end of the control lever 73 projects below the pivot 74 and is connected as at 76 to a flexible connector, as the chain 77. Said chain may extend around a guide sheave 78 and is attached to one of the arms of the bell crank lever 56 as shown in Fig. 7.

In the operation of the loom the vibrator connectors will move up and down as the vibrator gears rock about their centers. The pawls 45 will therefore move the ratchets 5 and the cam discs will be given an angular movement equal to the distance between a low point and the adjacent high point thereof. The levers 70 and 73 are in this way moved to any one of four different relative 10 positions to give the bottom of the control lever 73 four horizontal positions. The color slide 54 is thus moved positively to the left by the cam discs 48 and yieldingly to the right by spring 58. It is to be understood 15 that the boxes do not come to rest until the vibrator gears complete their oscillation but that the movement of control lever 73 is completed when the vibrator gears have been given approximately one-half of their movement, thus placing the color slide 54 in its final position before the boxes stop moving.

From the foregoing it will be seen that I have provided means in conjunction with the well-known Knowles head to complete 20 the movement of the color slide prior to the completion of the movement of the boxes, in this way affording more time for the bobbin which is to be placed in the exhausted shuttle to move to transfer position. Furthermore, it will be seen that the movements 25 of the levers 70 and 73 take place irrespective of the direction in which the vibrator gears 21 rotate, the low points of the cam discs being operatively disposed with respect 30 to the rounded ends 71 and 75 when the pivot 22 is to the left of the center of the vibrator gears and the high points of the discs co-operating with said rounded ends when the pivot 22 is to the right of the center of the 35 vibrator gears. Also, it will be seen that the pawls 45 which actuate the ratchets are mounted on the drop weight levers 40 which are only slightly different from the construction usual in the Knowles head.

Having thus described my invention it will be apparent that changes and modifications may be made therein by those skilled 40 in the art without departing from the spirit and scope of the invention, and I do not wish to be limited to the details herein disclosed, but what I claim is:

1. In a color indication mechanism for a weft replenishing loom having a vibrator lever, a vibrator gear rotatably mounted 45 thereon, a vibrator connector given operative movements by the vibrator gear, a shuttle box actuating mechanism operated by the vibrator connector, and a color slide, a drop weight lever to position the vibrator connector, a control lever operatively connected with the color slide, and means operatively related to the drop weight lever and the control lever to give the latter a plurality of positions as the vibrator moves under influence of the vibrator gear and to complete

the movement of the color slide prior to the movement of the shuttle box actuating mechanism.

2. In a color indication mechanism for a weft replenishing loom having a vibrator lever, a vibrator gear rotatably mounted thereon, a vibrator connector given operative movements by the vibrator gear, a shuttle box actuating mechanism operated by the vibrator connector, and a color slide, a drop weight lever for the vibrator connector, a cam disc, operative connections between the drop weight lever and the cam disc to actuate the latter as the vibrator connector moves, and a control lever operatively connected to the color slide and cam disc to give said slide completed movements prior to the completion of the movements of the shuttle box actuating mechanism.

3. In a color indication mechanism for a weft replenishing loom having a vibrator lever, a vibrator gear rotatably mounted thereon, a vibrator connector given operative movements by the vibrator gear, a shuttle box actuating mechanism operated by the vibrator connector, and a color slide, a drop weight lever for the vibrator connected to position the latter properly with respect to the vibrator gear, a pawl mounted on and movable with the drop weight lever, a ratchet to cooperate with the pawl, a cam disc moving with the ratchet, and a control lever operatively connected to the color slide and cam disc to communicate completed movements of the latter to said color slide prior to the completion of the movements of the shuttle box actuating mechanism.

4. In a color indication mechanism for a weft replenishing loom having vibrator levers, pattern mechanism therefor, vibrator gears rotatably mounted thereon, vibrator connectors given operative movements by the vibrator gears, actuators for the gears to move the same and connectors after the pattern mechanism has acted on the vibrator levers, and a color slide, a drop weight lever for each vibrator connector, a system of compound control levers operatively connected to the color slide, and means actuated by the drop weight levers and operatively related to the compound control levers to give the latter a plurality of positions, depending upon the positions of the vibrator connectors, said color slide receiving a completed movement prior to the completion of the movement of the vibrator connectors.

5. In a color indication mechanism for a weft replenishing loom having vibrator levers, pattern mechanism therefor, vibrator gears rotatably mounted thereon, vibrator connectors given operative movements by the vibrator gears, actuators for the gears to move the same and connectors after the pattern mechanism has acted on the vibrator levers, and a color slide, a drop weight lever

4
for each vibrator connector, a pawl and ratchet for each drop weight lever, a cam disc moving with each ratchet, and a set of compound control levers cooperating with the several cam discs and operatively connected to the color slide to give the latter a plurality of positions depending upon the position of the vibrator connectors, said color slide receiving a completed movement prior to the completion of the movement of the vibrator connectors.

6. In a color indication mechanism for a weft replenishing loom having a vibrator lever, a vibratory gear rotatably mounted thereon, a vibrator connector given operative movements by the vibrator gear, a shuttle box actuating mechanism operated by the vibrator connector, and a color slide, a ratchet, a pawl actuated by the connector,

and a device operatively connected to the color slide and movable with the ratchet to give the color slide a plurality of positions.

7. In a color indication mechanism for a weft replenishing loom having a vibrator lever, a vibrator gear rotatably mounted thereon, a vibrator connector given operative movements by the vibrator gear, a shuttle box actuating mechanism operated by the vibrator connector, and a color slide, a ratchet, a pawl actuated by the connector to move the ratchet intermittently but always in the same direction, and a device moved by the ratchet and operatively connected to the color slide to give the latter a plurality of positions.

In testimony whereof I have hereunto affixed my signature.

ALBERT A. GORDON.
